United States Patent Office.

E. R. MCKINNEY, OF LACON, ILLINOIS.

Letters Patent No. 64,239, dated April 30, 1867.

GATES.

The Schedule referred to in these Letters Patent and making part of the same.

TO WHOM IT MAY CONCERN:

Be it known that I, E. R. MCKINNEY, of Lacon, Marshall county, and State of Illinois, have invented an Improvement in Gates; and I do hereby declare that the following is a full and exact description thereof, reference being had to the annexed drawings, making part of this specification, in which—

Figure 1 represents a front view of gate when closed.

Figure 2 represents end view when open.

Figure 3 represents front view when fully opened.

Figure 4 represents the arrangement of the rods and lever on top bar connecting with latch for opening or closing.

The nature of my invention consists in so arranging and constructing the different parts of the gate that it may be opened or closed by a horseman without dismounting, or allow the passage of a vehicle without the necessity of the driver leaving his seat.

In appearance and mode of construction, (as to hinges, bars, &c.,) this gate will not vary much from those in ordinary use except in the height of the hinge post A, and the bar B, with its pendants C C and rods r r.

Attached to post A will be the bar B extending above the gate and parallel to the road. To each end of this bar will be attached, by hooks and rings s, the pendants C C, of such length they may be readily seized by any person riding and desirous of opening the gate. Toward the lower end of these pendants the rods r r will extend to the top bar of the gate, where they will connect with the lever L attached to latch of gate P by means of rods t t. This lever L is so arranged that moving on its fulcrum f the motion of either rod r will depress one end of lever, and by connecting-rods t depress the one end of latch P, (which has its fulcrum at o,) and elevate the other, thus opening the gate at will. By the use of the pendant C it can be closed with same facility. Between the second bar and latch is the spring x to insure fastening the gate when closed by dropping the latch into a slot or mortise, R, made to receive it.

What I claim, and desire to secure by Letters Patent, is—

The arrangement and combination of the cross-bar B near the top of hinge post, with its pendants C C, and rods r r, connecting with the lever L on the top bar of the gate, also device of lever L, with rods t t connecting with latch, as herein described.

E. R. MCKINNEY.
